UNITED STATES PATENT OFFICE

GEORGE C. DAVIS, OF CHICAGO, ILLINOIS, ASSIGNOR TO G. M. DAVIS REGULATOR COMPANY, OF CHICAGO, ILLINOIS, A CORPORATION OF ILLINOIS

VALVE HOUSING

Application filed March 26, 1926. Serial No. 97,510.

My invention relates to improvements in valve housings and the like and is particularly adapted for use in connection with those types of valves wherein a flexible diaphragm is used associated with a pressure chamber which responds to variations in pressure in some part of the line to control or operate the valve. One object of my invention is to provide a housing which will protect the working parts of the diaphragm and dash pot from the elements and avoid flooding, freezing and the like. Another object is to provide means for protecting the diaphragm when it is located in the same housing through which the material passes from the ejector effect of the rapidly moving gas or water. Other objects will appear from time to time throughout the specification and claims.

My invention is illustrated more or less diagrammatically in the accompanying drawings, wherein—

Figure 1 is a section through valve and housing;

Figure 2 is a plan view in part section 25 along the line 2—2 of Figure 1.

Like parts are indicated by like characters.

A is a valve housing communicating at one end with an intake pipe A¹ at the other end with an exhaust pipe A². A³ is a globe 30 contained within the housing and having valve seats A⁴ A⁵ through which gas or air or liquid may pass from the intake to the outlet side of the valve housing. A⁶ is the valve barrel adapted to extend through the 35 valve seats A⁴ A⁵ and carry valve discs A⁷ A⁸ with guiding fingers A⁹ adapted to guide the valve disc members toward and from the seats. A¹⁰ is a yoke on the valve in loose 40 engagement with a valve stem A¹¹ provided with a head A¹² to engage the yoke.

The valve stem A¹¹ extends up through an aperture B at the top of the valve housing into the pneumatic control chamber B¹ which is located in a housing B² having a cover B³ 45 and bolted onto the valve housing A so that an opening in the wall of the housing B² is in register with the opening B. B⁴ is a diaphragm held at its edges between flanges B⁵ B⁶ on the cover and housing. This diaphragm is reinforced by plates B⁷ B⁸ slidible

on a stud B⁹ and clamped against the shoulder B¹⁰ to compress the diaphragm by means of the threaded connecting rod B¹¹. The valve stem A¹¹ is pinned between the ears B¹² on the stud B⁹.

The cover B³ is open to permit the member B¹¹ to project outwardly above the diaphragm. A flange C surrounds this opening and projects upwardly from the cover. Associated with the member B¹¹ is a bell C¹ which extends downwardly outside the flange C and in all positions extends down below the top of the flange. This bell carries the member B¹¹ and terminates in a yoke C² pivoted on the lever arm C³ which arm in turn is pivoted on a fulcrum arm C⁴ on the cover B³ 60 and carries at its other end a yoke C⁵ having a bell C⁶ extending down and enclosing the upper end of a dash pot C⁷, C⁸ being a dash pot piston rod extending down from the yoke C⁵ within the bell C⁶ and carrying the piston C⁹ slidible in the dash pot C⁷.

The dash pot C⁷ is longitudinally adjustable in a split ring D, which ring may be clamped on the dash pot by means of a clamp screw D¹. This ring is pivoted at D² on an arm D³ carried by the cover B³ so that the dash pot is given the necessary reciprocating movement to compensate for the movement of the lever C³. An adjustable weight D⁴ is 80 carried by the lever C³.

Experience shows that when gas is drawn through the valve at a rapid rate of speed, if the opening between the valve housing and the diaphragm housing is unobstructed, there is a tendency of the pressure in the diaphragm housing to be reduced below the pressure in the valve housing as a result of the ejector effect of the rapidly moving gas and thus the adjustment for the diaphragm movement will 85 vary as the gas velocities vary even though the actual gas pressure may not vary. In order to prevent this, a fixed diaphragm E is inserted in the throat between the valve housing and the diaphragm housing. This fixed diaphragm comprises a cup-like member flanged at E¹ and held in place by clips E² associated with the cap screws E³ which hold the two diaphragms together. This cap is 90 perforated to permit passage of the valve 95 100

stem A¹¹ and is provided with a sleeve E⁴ extended upwardly along the valve stem A¹¹. This sleeve is in working contact with the valve stem, the contact being sufficiently light so that no appreciable friction is set up but such that air or gas circulation between the two chambers is minimized and the ejector effect completely dissipated. E⁵ is a pipe leading from the interior of the diaphragm housing 5 B to the pipe A¹ so that the pressure in the diaphragm housing is the same as the pressure in the intake pipe.

This arrangement of diaphragm in the throat between the diaphragm housing and the valve housing and the protecting mantle or bell protecting the open mouth or surface of the diaphragm and the dash pot though illustrated here as applied to a casing head regulator may be used either separately or in conjunction with many different valve arrangements and particularly the bell and housing for the diaphragm may be used in connection with any valve arrangement or mechanism where the valve is exposed to the 15 elements or dust, dirt and the like.

It will be evident that while I have shown in my drawings an operative device still many changes might be made in the size, shape, arrangement and disposition of parts 20 without departing materially from the spirit of my invention and I wish, therefore, that my showing be taken as in a sense diagrammatic.

The use and operation of my invention are 25 as follows:

Gas flow is in the direction from right to left in Figure 1. With the valve in the closed position as shown in Figure 1, gas does not pass through. Some gas, however, passes 30 through the by-pass pipe into the underside of the diaphragm chamber, exerting a pressure on the diaphragm. When the pressure exceeds a predetermined amount the diaphragm is forced up, opening the valve and permitting flow onward through the pipe A². Movement of the diaphragm and valve stem 40 is resisted by the dash pot, which is connected to the diaphragm and valve stem by the counterweighted lever and the pin extending up outwardly through the housing. To minimize friction both the dash pot and the sleeve surrounding the pin where it extends through the housing are inclosed by 45 long parallel-sided bells.

In order to protect the diaphragm chamber from the influence of gas movement eddy currents and the like which are set up in the valve chamber and which might transmit themselves through the open throat between 50 the valve chamber and the diaphragm chamber about the valve stem, the flexible sleeve shown is provided. This sleeve is held in position in the open throat, makes a flexible sliding contact with the valve stem, is long enough so as not to bind on the valve stem,

and is flexible enough so that it does not need to be accurately centered with respect to the valve stem and the throat but does give a substantially entire measure of protection and avoids the danger of impact of turbulent gas bodies upon the diaphragm, which impact might change the operation of the valve and make it less sensitive to the pressure variations to which it is intended to be sensitive.

I claim:

1. In combination with a valve and diaphragm controlling it, a housing for the diaphragm, a valve housing adjacent thereto, a control stem projecting upwardly from the diaphragm, a sleeve projecting upwardly from the diaphragm about said stem and out of contact therewith, a lever, a connection between said control stem and said lever, a bell, associated with said control stem, depending about said sleeve and out of contact therewith, a stem depending downwardly from said diaphragm, a valve associated with said valve stem, in said valve housing, said valve housing being formed with a valve seat in which said valve is in slidable engagement, 70 and flexible packing means, in slidable engagement with said last mentioned downwardly depending stem adjacent the point where it extends from the diaphragm housing into the valve housing.

2. In combination with a valve, a valve housing, a valve reciprocable therein, a diaphragm housing associated with the valve housing, there being a throat joining them, a valve stem passing through the throat upwardly from the valve, a diaphragm in the diaphragm chamber associated with the valve stem, a supply pipe adapted to conduct gas to the valve chamber, a by-pass pipe leading from the supply pipe outside of the valve chamber and discharging into the diaphragm chamber, a thin flexible gland closing the throat between the two chambers, the gland having a central flange in slidable engagement with the valve stem and anchored in position in the throat so as to be free to move in a plane perpendicular to the valve stem to compensate for variations in position of the valve stem.

3. In combination with a valve and diaphragm controlling it, a housing for the diaphragm, a valve housing adjacent thereto, a control stem projecting upwardly from the diaphragm, a sleeve projecting upwardly from the diaphragm about said stem and out of contact therewith, a lever, a connection between said control stem and said lever, a bell, associated with said control stem, depending about said sleeve and out of contact therewith, a stem depending downwardly from said diaphragm, a valve associated with said valve stem, in said valve housing, said valve housing being formed with a seat in which said valve is in slidable engagement and flexible packing means, engaging said 120 125 130

last mentioned downwardly depending stem adjacent the point where it extends from the diaphragm housing into the valve housing, the flexible packing being in slidable engagement with the stem and free to move in 5 directions perpendicular to the stem to prevent binding.

Signed at Chicago, county of Cook, and State of Illinois, this 11th day of March, 1926.
